UNITED STATES PATENT OFFICE.

NOAH M. CHEW, OF SOUTHPORT, INDIANA.

PLANT-SETTING MACHINE.

SPECIFICATION forming part of Letters Patent No. 406,336, dated July 2, 1889.

Application filed February 18, 1889. Serial No. 300,376. (No model.)

To all whom it may concern:

Be it known that I, NOAH M. CHEW, of Southport, county of Marion, and State of Indiana, have invented certain new and useful 5 Improvements in Plant-Setting Machines; and I do hereby declare that the following is a full, clear, and exact description thereof, reference being had to the accompanying drawings, in which like letters refer to like 10 parts.

My invention relates to the construction of machines intended to be used in setting out tomato and other plants, and will be understood from the following description.

15 In the drawings, Figure 1 is a top view. Fig. 2 is a section on the dotted line, Fig. 1. Fig. 3 is an inverted perspective view of the marker attached to the side of the planter. Fig. 4 is a detail view of the covering-wheels 20 and their brackets. Fig. 5 is a detail perspective view of the furrow-marker.

The frame-work of the machine consists of a rear platform P, supporting a seat s for the driver and two lower seats or cushions c for 25 the men who handle the plants, this platform running upon two pairs of covering-wheels w, each wheel set at an angle to the other upon stub-axles connected with brackets bolted to the under side of the platform, these being 30 of the ordinary construction. The front half of the frame-work consists of bars b b', parallel with the rear platform, and bolted to the under side of these are plows or furrow-markers f, of peculiar construction, these bars being 35 connected by diagonal braces 1 1, as shown.

t is the tongue, extending backward across the bars b b' and bolted thereto, its rear end pivoted to a link l', to the opposite end of which is pivoted an angle-lever l.

40 2 2 are iron braces connected on either side of the tongue by a pivot-bolt p', beneath the hammer-strap. The other ends of these braces are connected inside the cross-bars cb by pivot-bolts 3 and also by bolts 4, the latter 45 passing through slots in the braces to allow a longitudinal movement of the bolt when the plows are elevated by means of the lever, as hereinafter described.

r are foot-rests for the workmen.

50 b^x (shown in the dotted lines in Fig. 2) is a box for holding the plants, being set in the place indicated by the dotted lines in Fig. 1,

so as to be within reach of the plant-setters on either side. The cross-bars cb are bolted to the platform P, but their forward ends are 55 pivoted at p² to the bar b, thus forming a hinge at these points, and upon these rear pivot-bolts p² and the front pivot-bolt p' the forward half of the frame is swung up when the plows f are lifted out of the ground. 60

m is a marking device, a detail of which is shown in Fig. 3, connected by a bail and hooks to one side of the machine in front, and is intended to mark a center line for the next two furrows, as hereinafter described. 65

The platform P is cut out in front of the cushions c to allow room for the hands of the workmen in setting the plants in the furrows made by the furrow-marker f between and in front of the covered wheels w. The rear end 70 of the plow f is made with a bell-mouth about six inches across, and this is, first, to provide room for the partly-closed hand of the workman, as in setting the plants he works in the furrow between the plow and the covering-wheels, and, second, the swell of the upper 75 part of the plow operates to throw the earth away and keep it from falling upon and breaking or bruising the plants.

The lever l has a ratchet device and also a 80 toothed segment, of the usual construction, for locking the lever, and the driver, sitting in the seat s, by means of this lever, connected as it is by a link l' to the tongue, which is bolted to the bars b b', can lift the 85 furrow-markers up out of the ground when the end of the row is reached, and a reverse movement of the lever will drop the furrow-markers down again when the turn is made and the work is to be resumed. 90

The machine operates as follows: The driver sits upon the seat s, the plant-setters upon the cushions c, their feet resting upon the rests r, their legs extending across the intermediate bar b'. The plant-box b^x is within 95 easy reach of the operators' hands, and as the team pulls the machine forward the furrows are marked by the plows f and the workmen place the plants in the furrows thus made by the marker. The covering-wheels following 100 pack the earth around the plants, and the operation is repeated until the row is finished. While this is in progress the marker m marks a line parallel with the furrows made by the

plows *f*, and this line is intended to indicate the central line between the two next furrows, thus operating as a guide for setting the plow at each turn, the tongue of the machine being set directly over the line made by the marker *m*.
5

I am aware that covering-wheels and furrow-marking plows have been used in corn-planting machines; but I am not aware that 10 a machine combining the features of my invention and intended to provide a ready means for marking furrows and facilitating the operation of setting out plants and protecting them during the operation has been 15 ever before known or used.

What I claim as my invention, and desire to secure by Letters Patent, is the following:

1. A plant-setting machine comprising a working-platform mounted upon brackets 20 carrying a pair of covering-wheels on each side, a forward section beneath which are secured furrow-marking plows on each side hinged to cross-bars connected with the rear platform and also to a link pivoted to a lever

carried upon the rear platform, such platform 25 cut out on either side above the covering-wheels, with means for raising and lowering the front part of the machine from the rear part thereof, substantially as shown and described.
30

2. A plant-setting machine whose framework is composed of two sections hinged together, the rear section, a working-platform mounted on pairs of covering-wheels and providing seats for the workmen, a ratchet-lever mechanism secured thereto and connected to the forward section, furrow-plows secured beneath the latter, a box for holding the plants thereon, and a guide-marker for centering the next series of rows connected to one side 35 thereof, all combined substantially as shown and described.
40

In witness whereof I have hereunto set my hand this 9th day of February, 1889.

NOAH M. CHEW.
